UNITED STATES PATENT OFFICE.

ABRAM E. HOSTETTER, OF HOPE, KANSAS.

CONDENSER FOR MOTOR-VEHICLE RADIATORS.

Application filed June 21, 1926. Serial No. 117,558.

The object of the invention is to provide an appliance for use in connection with the radiators of motor vehicles, whereby the vapor, usually disappearing through the overflow, is trapped, condensed and automatically returned to the radiator, thus conserving the radiator contents which is particularly desirable where the radiator contains an anti-freezing solution, such as alcohol; to provide a construction wherein provision is made for the usual expansion of the radiator contents, when the vehicle engine is working, without exposing the same to evaporation; and to provide a construction of this character which is of extremely simple form and therefore susceptible of manufacturing and marketing at low cost.

With this object in view, the invention consists in a construction and combination of parts of which a preferred embodiment is illustrated in the accompanying drawings, wherein:

Figure 1 is a side elevational view of a motor vehicle radiator with the invention applied in operative position thereon.

Figure 2 is a longitudinal vertical sectional view through the condenser chamber.

Figure 3 is an enlarged front elevational view of the condenser chamber.

In the application of the invention, the pipe 10 is connected to the radiator 11 and extends rearwardly from the radiator, the remote terminal being downturned, as indicated at 12, and extending through the top of a condenser chamber 14, the latter being closed and the downturned end 12 of the pipe being sealed at the point where it passes through the top of the chamber.

Preferably, in the use of the present invention, the overflow pipe 15 of the radiator constitutes the means of connection between the latter and the pipe 10, being coupled to the pipe 10 as at 16. With the condenser chamber 14 there is connected an expandible bulb 17 having a neck 18 which engages a nipple 19 connected to the top of the condenser chamber, the nipple 19 and the neck 18 placing the bulb interiorly in communication with the condenser chamber.

As the radiator contents rise in temperature, the vapor passes through the pipe 10 and into the condenser chamber 14, where it condenses and ejects therefrom any air contained in the chamber which passes into the

bulb 17 which may be of rubber or any other readily expansible material. As long as the vapor remains in the pipe 10, however, there is no tendency to return the condensate contained in the condenser chamber 14 to the radiator, but when the temperature of the radiator contents drops and the amount of vapor produced is reduced, the vapor begins to condense in the pipe 10, and the atmospheric pressure on the exterior of the bulb 17 serves to compress the latter and, therefore, to return to the radiator through the pipe 10 the liquid condensate contained therein.

The device also serves as an overflow to take care of the expansion of the radiator contents and, by virtue of the bulb 17, functions to return the overflow to the radiator upon contraction of the contents due to cooling, as when the vehicle motor is stopped.

The condenser chamber 14 is mounted at a remote point from the radiator 11, thus providing for a long length in the pipe 10 and the exterior surface of this being exposed to the air, condensation begins when the vapor enters this pipe and the chamber 14 functions mainly as a trap for the condensate.

The invention having been described, what is claimed as new and useful is:

1. A device for the purpose indicated comprising, in combination with a radiator, a condenser comprising a closed chamber disposed at a point remote from the radiator, a pipe connected with the overflow of the radiator entering the condenser chamber and terminating adjacent the bottom thereof, and an expansible air chamber connected with the condenser chamber adjacent the top thereof.

2. A device for the purpose indicated comprising, in combination with a radiator, a condenser chamber, a pipe connecting the condenser chamber with the radiator, and an expansible air chamber in communication with the condenser chamber, the said air chamber consisting of a bulb formed of expansible material having a neck connected with a nipple formed on the condenser chamber.

In testimony whereof he affixes his signature.

ABRAM E. HOSTETTER.
